ABSTRACT: Door vent having valve plate for insertion into a circular door aperture, having two semicircular apertures, and semicircular valves hinged on a divider on opposite sides of the plate yieldingly closing the apertures, a center rod affixed to the divider member and extending in opposite directions, and circular louvered members on each end of the rod, to close off the door aperture.

RELIEF VALVE

This invention relates to a relief valve for relatively tightly fitted doors.

In the closing of a hinged door, the final movement of the door into the door frame, particularly when closely fitted, in a wide frame, results in a compression of the air in the path of the closing door. The degree of compression may vary with the rate of speed of the door movement in closing. If, as often is the case, a second door is located closely adjacent to the storm door, a relatively small volume of air is subjected to such compression. Any pressure build up resulting acts over the entire door area, and tends to resist the final closing. A similar effect results in the initial opening movement of the door, since the door tends to pull a vacuum. In vehicle doors where the doors are from 6 to 10 inches thick, the compression resulting from closing a door, with all windows closed, tends to prevent the door from closing beyond the secondary strike, and provides an uncomfortable pressure on the ear drums.

The present invention is directed to relieving the pressure which such doors tend to develop. The invention is further directed to relief of pressure as it is developed so that resistance to door closing or opening is obviated. The invention is further directed to an assembly which may be readily installed in any door and which may include two way relief.

The above and other novel features of the invention will appear more fully hereinafter from the following detailed description when taken in conjunction with the accompanying drawings. It is expressly understood that the drawings are employed for purposes of illustration only and are not designed as a definition of the limits of the invention, reference being had for this purpose to the appended claims.

In the drawings wherein like reference characters indicate like parts:

FIG. 1 is a sectional view of the assembly showing the door as in final closing movement;

FIG. 2 is a sectional view of the assembly showing the door as in initial opening movement;

FIG. 3 is an enlarged sectional view of the valve assembly;

FIG. 4 is an elevational view of a valve assembly;

FIG. 5 is a fragmentary enlarged view of a valve hinge; and

FIG. 6 is a fragmentary sectional view taken on the line 6-6 of FIG. 5.

Referring to FIGS. 1 and 2 there is shown a door 20 in which has been bored a circular aperture 22. Disposed in the aperture is a valve plate 24 having a disk portion 26 provided with semicircular or "D" shaped openings 28 and 30. The disk portion may have a flange or rim 32 which will nicely fit the bore 22. A double ended stud 34 affixed to the diametral divider 36 between the apertures 28 and 30 is of sufficient length to receive like louvre members 38, each of which is

provided with a circular centering flange 40, an annular seat 42, and a plurality of louvres 44. The louvre members and the valve plate are securely held in position by suitable cap nuts 46.

5 The valve plate is preferably provided with hinged flap valves 48 and 50 each of which are alike and provided with a rolled over edge 52 notched to receive complimentary hinge members 54 affixed to the divider 36, there being provided a hinge pintle 56. Each of the valves is provided with a coil 10 spring or springs 58 adapted to urge the valve to a closed position and located adjacent a hinge member 54, the coils being disposed about the pintle 56 and the ends bearing against the valve and divider 36 as shown.

The rim 60 of each valve is provided with a circular flange 15 62 within which is seated an arcuate gasket 64 adapted to uniformly seat upon the rim of its respective aperture, and to dampen any noise which might otherwise be generated by operation of the valves.

In FIG. 1, the valve 48 is shown in open relief position as 20 will occur upon closing of the door as in the direction of arrow A, resulting in a tendency to build up pressure, and thus cause air to flow as indicated by the air flow arrows C.

In FIG. 2, the valve 50 is shown in open position as would 25 occur in initial opening movement of a door, as in the direction of arrow B, the movement tending to create a slight vacuum causing air to flow as indicated by the arrows D to relieve such vacuum.

While a single form of the invention has been illustrated and 30 described, it is to be understood that the invention is not limited thereto. As various changes in the construction and arrangement may be made without departing from the spirit of the invention, as will be apparent to those skilled in the art, reference will be had to the appended claims for a definition of the limits of the invention.

35 I claim:

1. A door vent comprising a circular valve plate adapted for 40 insertion into a circular door aperture, and having substantially semicircular apertures therein, disposed above and below a diametral divider portion, semicircular valves hinged on said divider, one being disposed on one side of the divider and extending over one of the apertures, and the other being disposed on the other side of the divider, and extending over the other aperture, spring means urging each of said valves to closed position, a center rod affixed to the divider member 45 and extending in opposite directions, and a circular louvered member disposed on each end of the center rod, each of said louvered members having a peripheral annular seat, and a circular flange inwardly of the annular seat for insertion into a door aperture, the diameter of the flange being of the same 50 diameter as said valve plate.
